US0D1113514S

(12) **United States Design Patent** (10) Patent No.: **US D1,113,514 S**
(45) Date of Patent: ** Feb. 17, 2026

(54) **MOTION SENSOR**

(71) Applicant: **The ADT Security Corporation**, Boca Raton, FL (US)

(72) Inventors: **Kevin Greenland**, Philadelphia, PA (US); **Abhijeet Bhattacharya**, Camas, WA (US)

(73) Assignee: **The ADT Security Corporation**, Boca Raton, FL (US)

(**) Term: **15 Years**

(21) Appl. No.: **29/878,524**

(22) Filed: **Jun. 23, 2023**

Related U.S. Application Data

(63) Continuation of application No. 29/828,615, filed on Feb. 28, 2022, now Pat. No. Des. 994,519.

CLAIM

The ornamental design for a motion sensor, as shown and described.

DESCRIPTION

FIG. 1 is a front perspective view of a motion sensor; FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines are included for the purpose of illustrating portions of the motion sensor and form no part of the claimed design.

1 Claim, 6 Drawing Sheets
